[57] CLAIM

The ornamental design for a putter type golf club head, as shown and described.

DESCRIPTION

FIG. 1 is a front perspective view of a putter type golf club head showing my new design;

FIG. 2 is a rear perspective view thereof;

FIG. 3 is a top plan view thereof;

FIG. 4 is a bottom view thereof;

FIG. 5 is a front elevational view thereof;

FIG. 6 is a rear elevational view thereof;

FIG. 7 is an end elevational view thereof;

FIG. 8 is an end elevational view taken from the opposite side of FIG. 7;

FIG. 9 is a rear perspective view of a second embodiment of the golf club head of FIG. 1;

FIG. 10 is a rear perspective view of a third embodiment of the golf club head of FIG. 1; and,

FIG. 11 is a rear perspective view of a forth embodiment of the golf club head of FIG. 1.

The undisclosed views of embodiments 2, 3 and 4 are identical to that of embodiment 1.
